UNITED STATES PATENT OFFICE.

CHARLES D. MOSHER, OF NEW YORK, N. Y.

STEAM-BOILER.

No. 876,479.

Specification of Letters Patent.

Patented Jan. 14, 1908.

Application filed December 24, 1906. Serial No. 349,316

To all whom it may concern:

Be it known that I, CHARLES D. MOSHER, a citizen of the United States, residing at New York, in the county of New York and 5 State of New York, have invented certain new and useful Improvements in Steam-Boilers, of which the following is a specification.

This invention relates to water-tube boilers and it has for its object to provide such a construction and arrangement thereof as will facilitate the removal of tubes.

Of the accompanying drawings, Figure 1 represents a transverse section of a boiler 10 embodying my improvements. Fig. 2 represents a longitudinal section thereof.

In the drawings, 10 is an upper steam-and-water drum, 11 11 are two parallel water-drums with a furnace grate 12 and combustion-chamber between them, and 13 are curved water-tubes arranged in two groups with their lower ends fixed in the respective water-drums 11 and their upper ends fixed in the steam-and-water drum 10. These 20 tubes are adapted to pass through two rows of holes 14 in the drum 10 located opposite the upper ends of the two tube-groups and provided with detachable closers. One of these closers is represented conventionally at 25 15 in Fig. 1. They may be of any suitable type, but it is important to note that they should constitute actual stoppers for the holes 14 and that the tubes are removable only by opening the boiler through the removal of these closers, as will be hereinafter 30 explained. In the end of the drum 10 is a man-hole opening 16 having a removable cover or closer 17.

18 is the boiler-casing for guiding the 40 gases of combustion upwardly from the tube-groups around the steam-and-water drum 10 to a stack or uptake opening 19, this casing being separated a considerable distance from the drum 10 at points in line 45 with the tubes as they are projected through the openings 14.

The diameter of the steam-and-water drum 10 is less than the length of the tubes 13 so that the tubes are prevented from being 50 withdrawn by passing them into the drum 10 and then withdrawing them through the man-hole in the end of the drum as has been heretofore proposed, but the diameter of the drum together with the additional space be- 55 tween said drum and the walls of the casing

18 is sufficient to enable any tube 13, upon being disengaged at its lower end from the drum 11, to be passed upwardly through one of the holes 14 in the wall of the drum 10 after the closer 15 has been removed, whereupon the tube may be slanted lengthwise of the drum 10, as indicated in Fig. 2, and passed back entirely within the drum, and may then be removed from the boiler through the man-hole 16 in the end of the drum. The holes 60 14 sufficiently exceed the diameter of the tubes to permit the latter to be slanted in the manner indicated in passing them back into the drum. Certain of the tubes in the lower parts of the tube-groups may if desired 65 be removed by passing them up into the stack-opening 19 without withdrawing them through the end of drum 10.

My invention enables me to employ a steam-and-water drum of comparatively 75 small diameter in relation to the length of the tubes and thus retain strength and a minimum amount of material in this drum, together with relatively-long tubes, while at the same time it affords a means for taking 80 out tubes through the end of the steam-and-water drum. This enables the boilers to be used in situations from which they would be excluded if it were necessary to pass the tubes entirely through the upper shell of the steam-and-water drum. Such a situation is 85 encountered, for example, in locating boilers close up under the armored deck of a war vessel. I am also enabled to withdraw the tubes partly through the upper shell of the 90 drum without removing any parts of the boiler-casing, although of course openings may be provided in the casing if it is desired 95 to have convenient access to the closers 15. Such openings however would not be essential to the removal of tubes by the method described, when the parts are constructed and related in accordance with my invention.

Instead of curved tubes, straight tubes may be used as shown in my Patent No. 657,783, 100 with a plurality of rows of removal-holes, and various changes may be made in regard to the number and arrangement of tube-groups as well as in other particulars of construction.

The main purpose of curving the tubes 105 slightly, as shown, is to allow them to expand without warping and to make the zone of removal-holes 14 narrower than the zone of tube-ends in the tube-sheet. Excessive curvature however is to be avoided, as adversely 110

affecting the shape, location, and relative arrangement of the tube-group, lower drums, furnaces, etc.

It is to be noted that my improved arrangement for removing tubes does not restrict me to any particular shape or location of tubes. They may be either curved or straight, but the arrangement of some of the tubes at least is such that the protracted tube-lines extend above the top of drum 10, which would necessitate the lowering of the boiler to avoid an adjacent impervious deck or other obstruction if tube-removal could be accomplished only by withdrawing the tubes completely through the upper wall of the drum.

I claim:—

A steam boiler comprising an upper steam-and-water drum formed with an end opening having a removable cover and with holes in its upper wall for the passage of tubes, detachable closers for said holes, a lower water drum, a connecting group of tubes of greater length than the diameter of the steam-and-

water drum and so arranged with relation to the said holes that the lines of tube-passage 25 through the latter extend above the top of the steam-and-water drum, the said tubes being substantially smaller than the holes and removable by passing them through the holes partly outside of the boiler and then returning them into the drum and passing them out of the latter through the end opening, and a casing for the flue-gases, having a portion in the line of tube-removal and distant from the steam-and-water drum far 30 enough to permit the lower ends of the tubes to enter said drum but not so far as to permit complete upward withdrawal of the tubes from said drum.

In testimony whereof I have hereunto set 40 my hand in the presence of two subscribing witnesses, the 14th day of December, 1906.

CHARLES D. MOSHER.
